UNITED STATES PATENT OFFICE.

THOMAS E. MURRAY, JR., OF BROOKLYN, NEW YORK.

METHOD OF MAKING AXLE-HOUSING BLANKS.

Application filed February 2, 1923. Serial No. 616,437.

In the production of axle housing as described in my previous application No. 517,056 filed November 22nd, 1921, sheet metal is blanked to a proper outline and is then bent or drawn to form segments which by welding at their edges form the desired housings.

The present invention provides a blank or segments and a method of production for economically making such housings.

10 The accompanying drawings illustrate embodiments of the invention.

Fig. 1 is a plan of the sheet metal blank desired;

15 Figs. 2 and 3 illustrate methods of producing such a blank;

Fig. 4 is a side elevation, on a reduced scale, of the completed axle housing;

Fig. 5 is a cross-section of the same on an enlarged scale;

20 Fig. 6 is a fragmentary plan illustrating another method.

The housing has tubular end portions 1 with an intermediate enlarged portion 2 which has inward flanges 3 (Fig. 5) outlining an enlarged transverse opening 4. The dimensions and proportions are varied considerably according to the requirements of different users. The housing is made by placing two properly shaped segments edge to edge along the dotted line 5 (Fig. 4) and welding them. The present invention has to do with the production of these segments and of the blanks from which they are bent up.

The outline of a blank for producing the segment of Figs. 4 and 5 is shown in Fig. 1. It comprises an intermediate or body portion 6 with extensions or projections 7 of reduced width at the ends, the ends of the portion 6 being tapered along curves 8 to the width of the projections 7; and pointed projections 9 being provided at the sides of the body portion. Comparing Fig. 1 with Fig. 4, the body portion of the blank makes up the central part of the segment. The end projections 7 form the segments of the tubular ends 1 and the pointed projections 9 form the triangular portions 10 of the segments which carry the joint 5 between the segments all the way to the transverse opening 4.

50 The sheet metal blank of Fig. 1 may be stamped out directly from an integral strip 11. But this is productive of considerable wastage in scrap. In my former application above referred to I have described the making 55 of the blank of several parts, with the projections 7 or 9 butt welded onto the body por-

tion 6; the parts of the blank being first stamped out and then welded together. According to the present invention the blank is also composed of parts which are welded together; but they are welded together before the blanking operation. Also the present specific process ensures that the parts shall be in exact register, which was not easy to accomplish where they were first cut out and then welded. This idea of first welding the parts and then stamping out the blank may be applied in a variety of ways.

For example, in Fig. 2, a built up sheet is first produced by welding narrow pieces 12 onto the ends of a wider piece 13; the sheet thus produced being large enough to include the desired blank. The latter indicated as a whole by the numeral 14, and shown in dotted lines, is then stamped out in one operation. The result is a blank built up of three parts, a central wider portion and two narrower end portions. The economy of metal compared with Fig. 1 is evident.

Such economy may be even carried through 80 as shown in Fig. 3. In this case narrow end portions 12 are welded onto an intermediate portion 15 wide enough to include the regular width of the central portion of the blank but not the width of the pointed extensions; and 85 additional parts 16 are welded on the sides of the part 15 of a size to include said triangular projections. The building up of the pointed projections may be practiced without the building up of separate end projections, 90 and various other ways may be resorted to for accomplishing the desired result, balancing the cost of the welding operations against the saving in metal and adapting the operation to the particular shape of the blank desired. 95

Another mode of applying the principle is shown in Fig. 6. The central portion 6 of the finished blank, with the lateral projections 9 is blanked out first to the correct size, in doing which one can effect a considerable 100 economy of scrap by staggering the outlines. The ends 17 are left of a slightly greater width than that ultimately desired, and end portions 12, similar to those of Fig. 3, are 105 butt welded thereto and the final blank stamped out to the contour indicated in dotted lines.

The present application is directed specifically to the making of the composite sheet before blanking out the desired shape; the 110 former application, above referred to, containing claims broad enough to include this

method as well as the specifically distinct method described therein.

Though I have described with great particularity of detail certain embodiments of my invention yet it is not to be understood therefrom that the invention is restricted to the particular embodiments disclosed. Various modifications thereof in detail and in the arrangement of the parts may be made by those skilled in the art without departure from the invention as defined in the following claims.

What I claim is—

1. The method of producing a flat non-
15 rectangular sheet metal blank for a segment of an axle housing of uniform thickness throughout its extent and comprising a body portion with one or more lateral and end projections therefrom, said method includ-
20 ing the building up of a sheet of rectangular contour by welding together edge to edge pieces of the same thickness, each piece being larger than the portion of the sheet which it forms, and cutting off the edge portions of
25 said pieces to change the sheet to the desired contour.
2. The method of producing a flat non-
rectangular sheet metal blank for a segment of an axle housing of uniform thickness
30 throughout its extent and comprising a com-

paratively wide body portion having curved sides and comparatively narrow rectangular end projections, said method including the building up of a sheet of rectangular contour by welding together edge to edge a piece of
35 the said thickness shaped to include the body portion of the blank and other pieces of the same thickness shaped to include the end projections therefrom and cutting off the edge portions of said pieces to change the
40 sheet to the said contour of the blank.

3. The method of producing a flat non-
rectangular sheet metal blank for a segment of an axle housing of uniform thickness throughout its extent and comprising a cen-
45 tral comparatively wide body portion 6 having at its sides pointed lateral projections 9 and at its ends comparatively narrow rec-
tangular end projections 7, said method includ-
50 ing the building up of a sheet of rec-
tangular contour by welding together edge to edge separate pieces each of rectangular contour and of the same thickness, each piece being larger than the portion of the sheet which it forms, and cutting off the edge por-
55 tions of said pieces to change the sheet to the said contour of the blank.

In witness whereof, I have hereunto signed my name.

THOMAS E. MURRAY, JR.
